UNITED STATES PATENT OFFICE

CHARLES N. TEETOR, OF HAGERSTOWN, INDIANA, ASSIGNOR TO THE PERFECT CIRCLE COMPANY, OF HAGERSTOWN, INDIANA, A CORPORATION OF INDIANA

PISTON AND PISTON RING

Application filed June 21, 1930. Serial No. 462,711.

My invention relates to pistons and piston rings for internal combustion engines and more particularly to slotted rings for conveying the excess lubricant from the cylinder

5 wall and preventing oil pumping.

The principal object of my invention is to provide an improved slotted oil ring having the outer portions of the drain slots widened to provide narrow ribs having parallel sides and cylinder contacting surfaces of minimum area.

This and other objects of my invention will more fully appear from the following specification, reference being had to the accompanying drawings in which;

Fig. 1 is a detailed vertical section taken through part of a piston and ring embodying my invention;

Fig. 2 is a plan view of the ring; and

Fig. 3 is an edge elevation of the same.

The piston 4, which operates in the cylinder 5 of the internal combustion engine, may be of any desired form and as usual is provided with the ordinary compression rings

25 6. The bottom ring groove 7 has drain apertures 8 extending to the interior of the piston so that the excess lubricant scraped from the cylinder wall by my improved ring 9 may be returned to the crank case.

30 My ring 9 is provided with equally spaced slots 10 separated by triangular shaped bridges 11. The inner portions 10^a of the slots are narrow and of uniform width and the outer portions 10^b are wider than the inner portions and are of uniform width. In making the ring the narrow slots are first formed by a suitable tool. Then the outer portions of the slots are widened by circular saws to provide the very narrow ribs 12

35 which are of uniform width and have parallel sides. The bottom surfaces 13 of the slots on either side of the inner portions 10^a of the slots are arcuate, being deepest at points midway between the ends of the slots.

40 45 By widening the outer portions of the slots, the cylinder contacting surfaces of the ribs are materially reduced so that their combined area is less than one-half of the entire area of the exterior face of the ring. Thus the

50 pressure of the ring against the cylinder wall,

per unit area of contacting surface, is increased and the ring functions much more efficiently.

I claim:

55 In combination with an engine piston having an annular groove with apertures extending therefrom to the interior of the piston to permit the draining of excess lubricant from the cylinder walls, of a piston ring provided with elongated slots extending from its exterior face to the inner face of the ring, the inner portions of the slots being narrow and of uniform width and the outer portions being substantially wider and of uniform width to provide on either side of the outer portion 60 narrow ribs having substantially parallel sides and the bottoms of the slots on either side of the narrow portions being arcuate and having their deepest points midway between the ends of the slots.

65 70 In testimony whereof, I have subscribed my name.

CHARLES N. TEETOR.
